UNITED STATES PATENT OFFICE.

ANDREW J. KETELSEN, OF SEATTLE, WASHINGTON.

SPOUT AND FAUCET.

SPECIFICATION forming part of Letters Patent No. 714,585, dated November 25, 1902.

Application filed June 14, 1902. Serial No. 111,685. (No model.)

To all whom it may concern:

Be it known that I, ANDREW J. KETELSEN, a citizen of the United States, residing at Seattle, in the county of King and State of Washington, have invented certain new and useful Improvements in Spouts and Faucets; and I do hereby declare the following to be a full, clear, and exact description of the invention, such as will enable others skilled in the art to 10 which it appertains to make and use the same.

This invention relates to improvements in pouring-spouts for vessels, and particularly to a dividing-wall therefor, the object being the provision of means for controlling the 15 entrance of atmosphere to the vessel during the pouring operation.

With this and other objects in view the invention consists in combination, with a suitable vessel and its spout, of a tongue extending longitudinally thereof and curved at its 20 inner end beyond the inner end of the spout, so as to form an abutting wall for the contents of the vessel being discharged.

It also consists in certain other novel constructions, combinations, and arrangements of parts, as will be hereinafter fully described and claimed.

In the accompanying drawings, Figure 1 represents a vertical section through a vessel 30 the spout of which is provided with a tongue embodying the features of the present invention. Fig. 2 represents a transverse section on line 2 2 of an enlarged scale of Fig. 1. Fig. 3 represents a reduced view of a barrel, 35 illustrating a spigot in section employing a slightly-modified embodiment of the present invention. Fig. 4 represents an enlarged detail sectional view of the spigot shown in Fig. 3.

40 In the art to which the present invention relates it has been found desirable to provide means whereby the flow from the filling vessel will be caused to cease automatically in sufficient time to prevent the vessel being filled from overflowing, and in order to accomplish this result it has been proposed to permit entrance of atmosphere to the filling vessel through the discharge-spout thereof. The forms of devices heretofore employed 45 have either been found too expensive or inefficient, because of failure to successfully permit the entrance of air to the filling vessel,

and in order to produce a marketable article I have conceived the employment, in connection with any of the common forms of filling 55 vessels, of a tongue therefor, which shall divide the discharge-spout into two sections and provide against the entrance of liquid into the air-passage. To accomplish this I employ, as illustrated in the accompanying drawings, a 60 suitable tongue 1, adapted to be passed longitudinally within any suitable spout 2 for dividing the same into an upper air-passage 3 and a lower liquid-passage 4. The tongue 1 is of transverse concavo-convex form and is 65 made preferably of a flexible material, so as to have a laterally-spreading tendency. The tongue 1 is made of greater length than the spout 2 and is designed to have its outer end lie in the plane of the outer end of said spout, 70 the inner end of said tongue extending beyond the inner end of the spout and curving, as at 5, sufficiently for forming an abutting wall for the liquid, so as to prevent the same from entering the air-passage 3 during discharge. 75 The tongue 1 has its longitudinal edges contacting with the walls of the spout 2 and may be soldered at points, if desired; but it will be readily apparent that the laterally-expanding tendency of the said tongue will 80 cause it to firmly clamp the spout, whereby the tongue may be held in position.

In Figs. 3 and 4 I have illustrated a slightly-modified form of my invention, the same differing only in that the tongue 1', which is employed, is divided into two sections for permitting the passage of a plug 6, seated within a spigot 2'.

In operation liquid is caused to flow out of passage 4, striking against the abutting wall 90 formed by the curved end 5 of tongue 1 and being thereby limited against entrance into the passage 3, atmosphere passing through said passage for filling the space of the discharged liquid.

95 It will be apparent that many slight changes may be made in the form of tongue employed without departing from the spirit of the present invention, but that with all such changes it will be essential to retain the abutting portion formed by the curve 5 of the inner end of the tongue extending beyond the plane of the inner end of passage 3.

Having thus fully described my invention,

what I claim as new, and desire to secure by Letters Patent, is—

1. In a filling vessel, the combination with a suitable spout, of a concavo-convex flexible tongue arranged therein extending longitudinally thereof and beyond the inner end of the spout and curved to form an abutting wall within the vessel, substantially as described.
2. In a filling vessel, the combination with the spout thereof, of a concavo-convex flexible

tongue arranged therein having its edges engaging the walls of said spout, and dividing said spout into two sections, substantially as described.

In testimony whereof I hereunto affix my 15 signature in presence of two witnesses.

ANDREW J. KETELSEN.
